Primary Examiner — Robin V Webster*Assistant Examiner* — Rachel Voorhies(74) *Attorney, Agent, or Firm* — Christopher J. Volkmann; Kelly, Holt & Christenson, PLLC(57) **CLAIM**

The ornamental design for the paint spray gun, as shown and described.

DESCRIPTION

FIG. 1 is a perspective view of the paint spray gun.
 FIG. 2 is a front view of the paint spray gun.
 FIG. 3 is a back view of the paint spray gun.
 FIG. 4 is a right side view of the paint spray gun.
 FIG. 5 is a left side view of the paint spray gun.
 FIG. 6 is a top view of the paint spray gun; and,
 FIG. 7 is a bottom view of the paint spray gun.
 The broken lines in the drawings illustrate portions of the paint spray gun which form no part of the claimed design.

1 Claim, 5 Drawing Sheets(56)
